VEHICLE LICENSE PLATE LIGHT

John F. Stahl, Bridgeport, and Edward J. Nitsch, Camillus, N.Y., assignors to R. E. Dietz Company, Syracuse, N.Y., a corporation of New York

Filed Oct. 18, 1968, Ser. No. 14,074

Term of patent 14 years

Int. Cl. D12—99

U.S. Cl. D48—32

FIG. 1 is a plan view of a vehicle license plate light embodying our new design;

FIG. 2 is a side elevational view thereof, the other side being a mirror image thereof;

FIG. 3 is a front elevational view thereof as viewed from behind the vehicle;

FIG. 4 is a bottom plan view thereof; and

FIG. 5 is a rear elevational view thereof.

The dominant features of our design reside in the full line portions. Edge portions of the mounting pad, the plate bracket and the license plate are shown in broken lines in FIGS. 1, 2 and 4 for illustrative purposes only.

We claim:

The ornamental design for a vehicle license plate light, as shown and described.
